(57) **CLAIM**

The ornamental design for a dosing cup, as shown and described.

DESCRIPTION

FIG. 1 is a top front left perspective view of the dosing cup, showing my new design;

FIG. 2 is a front elevation view thereof;

FIG. 3 is a rear elevation view thereof;

FIG. 4 is a left side elevation view thereof, with the right side elevation view being a mirror image thereof;

FIG. 5 is a top plan view thereof;

FIG. 6 is a bottom plan view thereof; and,

FIG. 7 is a cross-sectional view thereof, taken along line 7-7 of FIG. 2.

The broken lines shown in the drawings depict an upper lip and a main body portion of the dosing cup that forms no part of the claimed design.
